UNITED STATES PATENT OFFICE.

NORMAN DODGE, OF EAST ORANGE, NEW JERSEY, ASSIGNOR TO MERGENTHALER LINOTYPE COMPANY, A CORPORATION OF NEW YORK.

TYPOGRAPHICAL MACHINE.

1,123,707.

Specification of Letters Patent.

Patented Jan. 5, 1915.

Application filed September 2, 1913. Serial No. 787,626.

To all whom it may concern:

Be it known that I, NORMAN DODGE, a citizen of the United States, residing at East Orange, in the county of Essex and State of New Jersey, have invented certain new and useful Improvements in Typographical Machines, of which the following is a specification, reference being had therein to the accompanying drawing.

10 My invention relates to typographical machines, such as linotype machines of the general organization represented in Letters-Patent of the United States, No. 436,532, to O. Mergenthaler, wherein circulating matrices are released from a magazine in the order in which their characters are to appear in print and then assembled in line together with spacers, the composed line transferred to the face of a mold, the mold filled 20 with molten metal to form a slug or linotype against the matrices which produced the type characters thereon, and the matrices and spacers thereafter returned through distributing mechanisms to the magazines from 25 which they started.

More particularly, it relates to machines of this kind equipped with means for delivering the matrices and spacers respectively to the assembling point in different 30 periods of time, and is specifically intended to effect the proper corresponding delivery of matrices and spacers, so as to avoid transpositions and the like.

In Letters-Patent of the United States to 35 Holbourns and Longhurst, No. 951,948, March 15, 1910, double or Janus-faced matrices are illustrated, and in connection therewith means whereby they may be reversed, in their passage to the assembler, so as to 40 present one set or another of their characters in operative position, as may be desired. The specific reversing means are in the form of an adjustable throat, provided with two 45 passages, one of them straight to permit the matrices to pass directly therethrough in the ordinary manner and unreversed, and the other grooved or rifled so as to reverse the matrices edge for edge and bring the opposite set of characters into operative 50 position. Obviously, the reversal of a matrix during its delivery requires a longer period of time than the mere passage of an

unreversed matrix, and accordingly I have provided means to retard or hasten the delivery of the spacers correspondingly, in 55 order to secure their proper co-operation and minimize the liability to transpositions, etc.

The means for controlling the period of delivery of the spacers may be embodied in widely different forms, and I have illustrated two such embodiments in the present instance. In one case I store the spacers in separate magazines located at different distances from the assembling point, and provide means for controlling their respective 65 escapements, whereby one or another is brought into action as the requirements demand. In the other case, I employ a single magazine, and a plurality of sets of differently timed escapement actuating devices, 70 and corresponding controlling means to render one or another set operative, as may be necessary.

In the accompanying drawings, I have shown my invention in preferred form and 75 by way of example, and as applied to the style of machine already described. However, many changes and variations may be made therein, and in its mode of application, which will still be comprised within its 80 spirit. For instance, the improvements may be similarly adapted to other forms of typographical machines, which handle type or dies instead of matrices, or they may be applied in various ways to other forms of 85 escapements, which control any kind of line elements, such as matrices, types and dies, as well as spacers. Generally speaking, I desire it to be understood that I do not limit myself to any specific form or embodiment, except in so far as such limitations are specified in the claims.

Referring to the drawings: Figure 1 is a partial front elevation of a linotype machine, partly broken away, having my invention applied thereto in one form; Fig. 2 is a detached front view on an enlarged scale, partly in section, of the specific improvements; Fig. 3 is a somewhat similar view, showing parts in different position; 100 Fig. 4 is a detached perspective of the spacer escapements, their actuating means, the controlling devices, etc.; Fig. 5 is an enlarged section, taken substantially on the line 5—5

of Fig. 2; Fig. 6 shows the different forms of spacers employed; Fig. 7 illustrates a Janus-faced matrix; and Fig. 8 is a detached perspective, illustrating another embodiment of my invention.

The matrices X (Fig. 7) are formed with characters X¹ and X² in their opposite edges, so that by reversing them either set may be brought into operative position.

10 The matrices are stored in the magazine G, and are released therefrom by the manipulation of the keyboard G¹ and delivered to the assembling belt G², from which in turn they pass into the assembler A, and in front 15 of the star-wheel B, all in the ordinary manner. Interposed between the belt G² and assembler A is the adjustable throat H, provided with reversing means, preferably consisting of two passages, one direct and the 20 other rifled, as best indicated by dotted lines in Figs. 1 and 2. The connected handle H¹ permits the throat H to be shifted so as to bring either passage into operation, as will be familiar to those skilled in the art.

25 The specific form of the devices so far described in itself constitutes no part of my invention, and may be substantially the same in construction and mode of operation as that disclosed in the previously mentioned patent to Holbourns and Longhurst.

In view of the fact that the period of delivery of a reversed matrix is somewhat greater than that of an unreversed matrix, my improvements contemplate a corresponding difference in the periods of delivery of the spacers designed to coöperate therewith, and mechanism for this purpose may be embodied in a variety of different ways, my preferred form being illustrated 40 in Figs. 1 to 6, inclusive, and involving the employment of differently constructed spacers stored in magazines located at different distances from the assembling point.

In Fig. 6, I have shown two kinds of 45 spacers Y and Y¹, substantially the same in construction, except that the sustaining ears Y² of the former are shorter than the ears Y³ of the latter, the different extent of these ears being availed of for distribution in the 50 manner subsequently to be described. The spacers Y are stored in the magazine C, mounted in substantially the ordinary position above the assembler A, and so that when released therefrom they pass directly 55 into the line and in front of the star-wheel B. The spacers Y¹ are stored in the magazine C¹, located immediately above the magazine C, and so that spacers released from either magazine pass directly down- 60 ward and through the common chute C² to the assembling point. It will be apparent, due to the different distances traversed, that a spacer Y from the nearer magazine C will be delivered into the line in a briefer period 65 than a spacer Y¹ from the farther maga-

zine C¹. Accordingly I arrange for the employment of the spacers Y in connection with the speedier unreversed matrices, and of the spacers Y¹ in connection with the slower reversed matrices, and preferably I 70 effect the shifting from one spacer magazine to another by connections from the reversing throat H. The escapement devices of the two spacer magazines are of the ordinary form and may be described together. 75 Each consists of a pair of vertically reciprocable pawls F connected to the pivoted rocker frame F¹, which latter is shifted first in a downward direction to engage the pawls F under the ears of the outermost 80 spacer in the magazine, and next rises and releases the spacer, which then drops through the chute C² to the assembler. In the present instance, I provide means which would 85 actuate both rocker frames F¹ simultaneously, were it not for the locking mechanism hereafter set forth. The actuating devices (see Fig. 2) are controlled by the ordinary spacer key or bar D, the manipulation 90 of which permits the constantly rotated roll D¹ to engage the cam D², connected to the reed D³ and escapement lever E, all in the ordinary manner. The inner end of the lever E is formed in two branches E¹ and E², designed to engage loosely beneath the projecting portions F² of the respective rocker frames F¹ of the magazines C and C¹. The first effect of the engagement of the cam D² with the roll D¹ is to elevate the reed D³ and thus to lower the inner end of the lever E, 100 after which the return movement of the reed elevates the inner end of the lever E, that is to say, the escapements of both magazines would be completely actuated thereby, if one of them were not held temporarily out 105 of operation.

Connected to the reversing throat H, in such manner as to partake of its adjusting movement, is the arm H², formed at its upper end in two branches H³ and H⁴, the 110 former adapted in one position of the arm to engage with the rocker frame F¹ of the lower magazine C, and the latter in the other position of the arm to engage with the rocker frame of the magazine C¹. The parts 115 are so arranged and designed, that when the throat is in position to permit a matrix to pass directly and unreversed into the line, the escapement of the magazine C¹ will be locked against action, and spacers Y from 120 the lower magazine C will be delivered; and when the throat is adjusted to reverse the matrices, the escapement of the magazine C will be locked and spacers Y¹ from the magazine C¹ will be delivered. Fig. 2 shows 125 the rifled passage of the throat in position to reverse the matrices and the escapement of the lower magazine C as locked, and Fig. 3 illustrates the partial operation of the upper escapement in such circumstances, 130

namely, after its first downward movement due to the descent of the inner end of the lever E. It will be understood that the operation of the escapement of the magazine C will be permitted in a similar manner, when the throat H is adjusted to its other position, and thereby the escapement of the magazine C¹ is held against action.

After the line has been cast and the matrices are lifted to their distributing mechanism, the spacers Y and Y¹ are returned laterally to their place of storage in the usual way, as disclosed for instance in the Mergenthaler patent previously mentioned. Referring to Figs. 1, 2 and 5, during this lateral movement they are supported by their sustaining ears in the grooves P, which in the present instance lead directly to the upper magazine C¹. Diverging from the grooves P and at a point in advance of the magazine C¹ are downwardly inclined grooves P¹ which lead to and communicate with the magazine C. It will be noted that the grooves P are of greater depth and extent than the grooves P¹, corresponding to and coöperating with the previously mentioned sustaining ears Y² and Y³ of the spacers Y¹ and Y, which are similarly of different extent. As the spacers Y and Y¹ move laterally, both kinds are supported by the engagement of their ears with the groove P until they reach the groove P¹, at which point the shorter ears Y² will enter and pass down the groove P¹, and the spacers Y will thus be restored to the magazine C, whereas the longer ears Y³ will pass over the entrance to the groove P¹ and the spacers Y¹ will therefore be restored to the magazine C¹.

In Fig. 8 I have shown a modified form of construction. In this instance a single spacer magazine is employed, and I rely upon differently timed escapement actuating devices to alter the delivery periods of the spacers, these devices being connected to and under the selecting control of the reversing throat. The spacer escapement is actuated by the lever E¹⁰ and reed D¹⁷ pivotally connected thereto at the point D¹⁸. The lower end of the reed D¹⁷ is controlled by the link or slide H¹⁰ connected to the reversing throat, in such manner that its position depends upon whether the rifled or plain passage is in operation. Immediately beneath the reed D¹⁷ are mounted two vertically reciprocable bars D¹⁵ and D¹⁶, either of which is adapted to operate the reed D¹⁷ according to the position of the slide H¹⁰. The bar D¹⁵ is connected to an actuating element comprising the cam D¹² arranged to be rotated by the roll D¹⁴, and the bar D¹⁶ to an element comprising the cam D¹¹ adapted to be rotated by the other roll D¹³. The respective elements are simultaneously controlled by the single double

branched connection D¹⁰ to the spacer key, in such manner that when the latter is operated both of the cams D¹¹ and D¹² are brought into operative relation to their respective rolls D¹³ and D¹⁴, thus effecting the simultaneous operation of both the bars D¹⁵ and D¹⁶. It will be observed that the cam D¹¹ is of less size and circumference than the cam D¹², and consequently that the bar D¹⁶ will be reciprocated more quickly or in a less period of time than the bar D¹⁵. This difference in the time of actuation is transmitted to the reed D¹⁷, according to the position of the slide H¹⁰, and a corresponding difference in the speed of delivery of a spacer is thus effected. As shown in Fig. 8, the rifled or reversing passage of the throat H is in action, and the reed D¹⁷ is in position to be reciprocated by the slower cam D¹². Upon the adjustment of the throat H to bring its plain passage into action, the reed D¹⁷ is shifted so as to be reciprocated by the quicker cam D¹¹.

As previously stated, I have shown my invention only in preferred form and by way of example, and as adapted to a specific kind of machine, but obviously many alterations and modifications therein and in its mode of application will suggest themselves to those skilled in the art without departure from its scope.

Having thus described my invention, its construction and mode of operation, what I claim and desire to secure by Letters Patent of the United States is as follows:

1. In a typographical machine comprising spacers and type or matrices adapted to be assembled in line, the combination of means for reversing the type or matrices in their passage to the line, and means controlled automatically thereby for increasing the period of delivery of the spacers to the line.

2. In a typographical machine comprising spacers adapted to be delivered to the line in different periods and type or matrices adapted to be reversed in their passage to the line, means for reversing the type or matrices and automatically controlling the periods of delivery of the spacers.

3. In a typographical machine comprising spacers and reversible type or matrices, the combination of spacer delivery means, with means for reversing the type or matrices, and automatically controlling the spacer delivery means.

4. In a typographical machine, the combination of a magazine to contain type or matrices, two additional magazines to contain justifying spacers, and means for rendering the spacer magazines active and inactive alternately.

5. In a typographical machine, the combination of a magazine to contain type or matrices, two additional magazines to con-

- tain justifying spacers, and each provided with an escapement, and means for operating the escapements of one or another of the spacer magazines at will.
- 5 6. In a typographical machine, the combination of a magazine to contain type or matrices, two additional magazines to contain justifying spacers and each provided with an escapement, and means for locking 10 the escapements of one or the other of the spacer magazines against action at will.
- 10 7. In a typographical machine, the combination of a magazine to contain type or matrices, two additional magazines to contain justifying spacers and each provided with an escapement, common operating devices for the escapements of both spacer magazines, and means for locking and unlocking the escapements alternately.
- 15 8. In a typographical machine comprising reversible type or matrices, the combination of two spacer magazines arranged at different distances from the assembling point, with means for reversing the matrices and for bringing one or the other of the spacer magazines into action.
- 20 9. In a typographical machine comprising reversible type or matrices, the combination of two spacer magazines arranged at different distances from the assembling point and each provided with an escapement, means for reversing the type or matrices, and devices controlled thereby for governing the operation of one or the other 25 of the said escapements.
- 25 10. In a typographical machine comprising reversible type or matrices, the combination of two spacer magazines arranged at different distances from the assembling point and each provided with an escapement, means for reversing the type or matrices, and devices controlled thereby for locking and unlocking the said escapements alternately.
- 30 11. In a typographical machine comprising reversible type or matrices, the combination of two spacer magazines arranged one above another and each provided with an escapement, means for reversing the matrices, and devices controlled thereby for preventing the operation of one or the other 35 of the said escapements.
- 35 12. In a typographical machine comprising type or matrices and justifying spacers, the combination of a magazine to contain the type or matrices, two additional magazines to contain the justifying spacers, and means for returning the justifying spacers to their proper magazines.
- 40 13. In a typographical machine, comprising type or matrices and justifying spacers, the latter differing in form from each other, the combination of a magazine to contain the type or matrices, a plurality of magazines to contain the justifying spacers, and 45 means for returning the justifying spacers to one magazine or another according to their form.
- 50 14. In a typographical machine comprising type or matrices and justifying spacers, the combination of a magazine to contain the type or matrices, two additional magazines to contain the justifying spacers, guides or ways leading to each of the spacer magazines, and means whereby the spacers are delivered to the guides or ways of one or another of the magazines.
- 55 15. In a typographical machine, the combination of a magazine to contain type or matrices, two additional magazines each containing a set of justifying spacers, the two sets of justifying spacers being formed with projecting ears of different extent, and two series of guides to support the spacers by their ears in their return to their respective magazines, one series of guides diverging from the other series and adapted to receive the spacers with the shorter ears.
- 60 16. In a typographical machine, the combination of a magazine containing type or matrices, two additional magazines each containing a set of justifying spacers, the two sets of spacers having projecting ears of different extent, and passages leading to each of the spacer magazines, one of said 65 passages being extended from the other, whereby the spacers are caused to traverse one passage or the other according to the extent of their ears.
- 65 17. In a typographical machine, the combination of a magazine containing a set of type or matrices, and two additional magazines each containing a set of justifying spacers formed with projecting ears, the ears of one set of spacers being of greater extent than the ears of the other set, for the purpose described.
- 70 18. In a typographical machine, the combination of a magazine containing a set of type or matrices, two additional magazines each containing a set of justifying spacers formed with projecting ears, the ears of one set of spacers being of greater extent than the ears of the other set, and means for separating the several sets of spacers by their ears to permit their return to the proper magazine.
- 75 19. In a typographical machine comprising spacers and reversible type or matrices, the combination of an adjustable reversing throat formed with different passages through which the type or matrices pass, and means controlled automatically by the throat for causing the delivery of the spacers in different periods when the throat is adjusted to bring one or another of its 80 passages into operation.
- 80 20. In a typographical machine comprising spacers and reversible type or matrices, the combination of two spacer magazines,

an adjustable reversing throat formed with
different passages through which the type
or matrices pass, and means for causing
the delivery of spacers from one magazine
5 or another according to the adjustment of
the throat.

In testimony whereof I have affixed my
signature in presence of two witnesses.

NORMAN DODGE.
